UNITED STATES PATENT OFFICE

164,578

STRIP OF ELECTRICAL INSULATING
MATERIAL

George E. Henning, Baltimore, Md., assignor to
Western Electric Company, Incorporated, New
York, N. Y., a corporation of New York

Application September 7, 1949, Serial No. 4,881

Term of patent 14 years

(Cl. D54—2)

To all whom it may concern:

Be it known that I, George E. Henning, a citizen of the United States, residing in the city of Baltimore, in the State of Maryland, have invented a new, original, and ornamental Design for a Strip of Electrical Insulating Material, of which the following is a specification, reference being had to the accompanying drawing, forming a part thereof, in which:

Fig. 1 is a perspective view of a strip of electrical insulating material embodying my new design; and

Fig. 2 is an enlarged sectional view taken along line 2—2 of Fig. 1.

I claim:

The ornamental design for a strip of electrical insulating material, substantially as shown.
GEORGE E. HENNING.
